UNITED STATES PATENT OFFICE.

JOHN EDWARD WATSON, OF PHILADELPHIA, PENNSYLVANIA.

ATTACHMENT DEVICE FOR ELECTRIC FIXTURES.

Application filed May 26, 1922. Serial No. 563,895.

To all whom it may concern:

Be it known that I, JOHN EDWARD WATSON, a citizen of the United States, residing in Philadelphia, Pennsylvania, have invented certain new and useful Improvements in Attachment Devices for Electric Fixtures, of which the following is a specification.

Various forms of electric connecting devices have been made prior to my present invention for the purpose of enabling the attachment of electrically operative apparatus to receive electric current from electric lighting fixtures without interfering with the use of the fixtures for lighting purposes or without destroying the ornamental character of the fixture. Certain of these prior art devices include socket portions which are secured, as by solder, to the main shells or body portions of the fixtures and have ornamental parts for closing the entrance to the sockets when the latter are not desired for use for attachment purposes. Others of said prior art devices have ornamental parts which hang or depend entirely outside of the main body of the fixture, said ornamental parts including the attachment sockets.

One object of my present invention is to provide an improved attachment device, for the above mentioned purpose, which can be made to readily fit within the main body portion of an electric fixture and which can be quickly and firmly secured in place; the arrangement and construction being such that parts thereof will hold or bind the sections of the fixture body together and will also support the socket proper independently of the electric conduit wires so that no weight or strain will be imposed on said wires during use of the device for attachment purposes.

Another object is to make the parts of my invention of a neat and durable construction and so that it can be quickly and easily installed in a proper manner by a workman without requiring great skill.

In the accompanying drawings illustrating my present invention,

Figure 1 is an elevational view partly in central vertical section showing my invention embodied in an electric fixture.

Figure 2 is an elevational view showing features of my invention, an ornamental closure portion for the socket and lower

end of the casing being illustrated in dot-and-dash lines.

Figure 3 is a detail sectional view of the socket casing illustrated in Figures 1 and 2.

Figure 4 is a section taken on the line 4—4 of Figure 1.

Figure 5 is an elevational view of a modified form of socket casing which I may employ.

Figure 6 is a top plan view of the casing shown in Figure 5 and

Figure 7 is a sectional view of a socket casing, of the same general type as shown in Figures 1, 2 and 3, illustrating additional holes or apertures for a purpose hereinafter described.

In Figures 1 to 4 inclusive of the drawings, 10 represents a main body of an electric fixture, such as the metallic body of a hanging electric light fixture; said body 75 being made hollow in the form of a shell and including a lower section 11 and a top section 12. The lower section 11 is open at its top and terminates in an upper edge portion 13 which is shaped to provide a 80 ledge or shoulder 14 below its extreme top edge 15. The top section 12 is open at its bottom and is provided with a surrounding skirt flange 16 which telescopically fits within the confines of the top edge portion 13 85 and abuts the ledge 14 as clearly shown in Figure 1.

The bottom 17 of the lower body section 11 is provided with a hole 18 which is preferably located directly under a hole 19 in the extreme top 20 of the body section 12. A suspension loop 21 has a base 22 providing a hole 23. The hole 23 has an enlarged internally screw threaded portion 24 into which is screwed the upper end portion of 95 an externally screw threaded tube 25. The tube 25 extends through the hole 19 into the space within the body 10 and at its lower end is screwed into the upper end of a turn-buckle or hickey 26.

My improved attachment device includes a portion 27 which may be made in the form of a casing of metal as illustrated and which has a part 28 of greater diameter than that of the hole 18. The part 28 in the form illustrated is made by bending or otherwise producing a flange on the lower open end of the casing 27, the part of the casing above the flange being of such diameter as to freely pass through the hole 105 110

18 into the space within the body 10. The flange 28 serves to limit the upward movement of the casing by abutting the outer surface of the bottom 17 of the body 10.

5 An electric connecting structure or inner socket 29 is located within the confines of the socket casing 27 and, in the form of the structure illustrated, includes a metallic screw threaded portion 30. A shell 31 of insulating material is interposed between the casing 27 and the screw threaded portion 30 of the socket 29. The lower end of the shell 31 preferably depends below the lower ends of the portion 29 and casing 27 10 and the upper end of the insulating shell 31 preferably abuts a shoulder such as the shoulder 32 of the body portion 33 of the connecting structure 29. The shell 31 can be forced into place and be held by friction 15 so as not to fall, or if desired this shell can be otherwise suitably secured to either the casing or structure 29.

The top of the connecting structure 29 includes a clamp 34 and portions 35 which are held by the clamp to the outer threads of the lower end of a nipple 36 at a position within the casing 27. The nipple 36 extends upwardly through a hole 37 in the top of the casing. Lock nuts 38 and 39 on the 20 nipple 36 are located adjacent opposite surfaces of the top of the casing 27 and secure the nipple to the casing 27. The upper end of the nipple is screwed into the lower end of the hickey 26.

35 It will be noted that by providing a structure as described and illustrated, the casing 27 serves to support the lower section 11 of the fixture body 10, and since the casing is connected to the base of the loop 21 through 40 the medium of the nipple 36, hickey 26 and tube 25, the sections of the body will be held and clamped together.

The main electric conduit wire 40 leads into the fixture through the hole 23, tube 45 25 and hickey 26, and branch electric conduit wires 41 and 42 are connected to the main conduit 40 and lead through the hickey 26 and nipple 36 into the casing 27 where they are electrically connected to the structure 29 and respectively electrify the portion 30 and a contact member 43, said portion 30 and member 43 being electrically insulated from each other.

Other branch conduit wires are connected 55 to the main conduit 40 and lead out of the body 10 through holes 44 to supply electricity to lamps which can be supported on arms 45 which are attached to the body 10.

I provide an ornamental closure for the 60 parts at the bottom of the fixture and said closure can remain in place when it is not desired to connect any electrical apparatus to the connecting structure. Said closure in the form illustrated includes a screw threaded plug 46, preferably of insulating material,

which screws into the portion 30. A screw 47 leads through the plug 46 and through a cap 48 into a tapped opening in a knob 49. The plug, cap, and knob are keyed or otherwise secured together against relative rotation. The cap 48 preferably has a recess 50 into which the lower ends of the casing 27 and shell 31 extend, said recess being surrounded by a flange 51 which abuts the lower surface of the fixture body 10 when the plug 75 is screwed in so that all parts of the device can be concealed and the cap 48 and knob 49 of said closure simulates a portion of the body 10.

If it is desired to make an electric connection for any electrical apparatus, such for example as for an electric vacuum cleaner, percolator, fan, toaster or the like, the closure can be removed by removing the plug 46, and then the connecting plug on the 80 conduit or extension wire of the apparatus can be inserted in the socket so that said latter plug makes electric contact with the portion 30 and contact 43.

In Figures 5 and 6, I have illustrated at 27^a 90 a casing or portion which can be made of stamped, cut or pressed metal or other suitable material which can be used in lieu of the casing 27 above described. Owing to the open or cage-like character of the portion 27^a the wires 41 and 42 for the socket need not enter through the nipple but can lead to the inner socket through the spaces between the parts 52. The parts 52 have flanges 28^a for abutment with the bottom of 100 the fixture body in the same manner as the flange 28 of the casing 27.

In Figure 7 is illustrated a form of casing 27^b 105 substantially similar to the casing 27 with the exception that it is provided with apertures 53 through which the socket-connecting wires can pass if it is not desired to pass them through the nipple.

It will be understood that if the nipple is not used for a passage for the socket-connecting wires, said nipple if desired can be made solid instead of tubular. Furthermore while I have described the inner socket portion connected to the nipple by the clamp 110 34 it will be understood that any other suitable connecting means may be employed and the inner socket can be of any of the usual or well known forms of construction.

Having thus described my invention, what I claim as new and desire to secure by Letters Patent is:—

1. In combination with an electric fixture of the character described having a fixture body including two sections, with electric lamp-supporting means, of a connecting device for binding said sections together, one of said sections having a hole therein, said device having a casing extending through said hole and a part on the casing for binding abutment with said latter section, said 125 130 135

device including a portion connected to the other section, said device having auxiliary electric attachment means connected thereto and located within the confines of said casing.

2. In combination with an electric fixture of the character described having electric lamp-supporting means and a fixture body including two shell sections each provided with a hole, of an electrical connecting device for binding said sections together independently of a ceiling or wall, said device having a casing extending through one of the holes with a part for abutment with the section including said latter hole, said device including a portion in connection with said casing and extending through the hole in the other section with a part abutting said latter section, said device having auxiliary electric attachment means connected thereto within the confines of said casing.

3. In combination with an electric fixture of the character described having electric lamp-supporting means and a fixture body including two shell sections each provided with a hole, of an electrical connecting device for binding said sections together, said device having a casing extending through one of the holes with a part for abutment with the section including said latter hole, said device including a portion in connection with said casing and extending through the other of said holes, a part of said portion being screw threaded and abutting the other of said sections whereby the sections are held together by said device, said device having auxiliary electric attachment means connected thereto within the confines of said casing.

4. In an electric fixture of the character described having electric lamp-supporting means, a hollow fixture body made in shell sections, said sections having holes therein; means for suspending said body whereby the body can be hung in a position remote from a ceiling or wall; an auxiliary electric attachment socket having a casing extending into the body through one of said holes with a part for abutting the body out-

side the confines of said latter hole; and connecting means having a part extending through the other of said holes and connected to said casing, said connecting means having a portion abutting the outer surface of the section which includes said latter hole, whereby the shell sections are held together by said latter portion, said casing, and the connecting means independently of said suspension means.

5. In combination with an electric fixture having electric lamp-supporting means and a fixture body including two sections, of an electrical connecting device for binding said sections, one of said sections having a hole therein, said device having a portion extending through said hole and a part for binding abutment with said latter section, said device including a portion connected to the other section, said device having auxiliary electric attachment means connected thereto within the confines of said fixture body and accessible through said hole; and a readily detachable closure for normally concealing said auxiliary electric attachment means and simulating a portion of said fixture body.

6. An attachment device for binding together the sections of an electric lighting fixture shell body, said device having portions adapted to be inserted through holes in the said sections with parts for binding abutment with the sections at positions adjacent the holes, said device including auxiliary electric attachment means accessible through one of said holes and a closure device for covering the auxiliary attachment means and serving when in said covering position to simulate a portion of the fixture body, said closure device being readily movable to allow access to said auxiliary attachment means.

In testimony whereof, I have signed my name to this specification, in the presence of two subscribing witnesses.
